UNITED STATES PATENT OFFICE.

WILLIAM A. BROWN, OF PHILADELPHIA, PENNSYLVANIA.

HEAT-FOCUSING DEVICE FOR COMBINED ELECTRIC LAMPS, HEATERS, AND BLOWERS.

Application filed September 14, 1922. Serial No. 588,106.

To all whom it may concern:

Be it known that I, WILLIAM A. BROWN, a citizen of the United States, residing in the city and county of Philadelphia, State 5 of Pennsylvania, have invented a new and useful Heat-Focusing Device for Combined Electric Lamps, Heaters, and Blowers, of which the following is a specification.

My invention consists of a novel construction of a heat focusing device or telescopic casing for combined electric lamp, heater and blower and consists of a novel collocation of an electric heater and an electric blower located in proximity thereto in conjunction with electric lighting devices and an outer casing or lamp shade telescopically supported with respect to the open ended guard which may enclose and support the electric heater, whereby the heat emanating 10 from the heater can be directed or focused upon any desired point upon adjusting telescopically the outer casing or cylinder, the heating and blowing devices and their adjuncts being preferably adjustably mounted 15 on a suitable support, so as to focus the heat upon the desired point.

It further consists of other novel features of construction and advantage, all as will be hereinafter fully set forth.

30 For the purpose of illustrating my invention, I have shown in the accompanying drawings, forms thereof which are at present preferred by me, since the same will give in practice satisfactory and reliable 35 results, although it is to be understood that the various instrumentalities of which my invention consists may be variously arranged, and organized and that my invention is not limited to the precise arrangement 40 and organization of these instrumentalities as herein shown and described.

Figure 1 represents a vertical sectional view of a heat focusing device or telescopic casing and a combined electric lamp, heater 45 and blower to which the same is applicable embodying my invention.

Figure 2 represents a plan view of Figure 1, with the lights omitted.

Figure 3 represents a sectional view, 50 partly in elevation of the device seen in Figure 1, showing the shade or outer casing in a horizontal plane.

Figure 4 represents a vertical sectional view of another embodiment of my invention.

Figure 5 represents a plan view of Figure 4, with the lights omitted.

Figure 6 represents a sectional view of Figure 4, partly in elevation, showing the heater, blower and their adjuncts supported 60 in a horizontal plane.

Figure 7 represents a side elevation partly in section of another embodiment of my invention.

Similar numerals of reference indicate 65 corresponding parts.

Referring to the drawings,

1 designates my novel construction of heat focusing device or telescopic shade or casing for a combined electric lamp, heater 70 and blower, the same comprising a standard, a support, or bracket 2, upon which one or more arms as 3 are pivotally supported at the point 4 by means of a threaded stem or bolt having a nut as 5 which can be tightened to lock the device in any desired position or at any desired angle.

The terminals of the arms 3 are flared outwardly as indicated at 6 and within them is supported the blower or motor casing 7 80 having a shaft of the usual character which is provided with the fan or blower 8.

The blower may be supported by any suitable means, as the upper and lower arms or brackets 9 and 10, and the outer terminals 85 of the arms 6 are secured in any suitable manner to the open ended guard 11, which is provided at a plurality of points, as four, seen in Figure 2, with the longitudinally extending grooves or seats 12, in which are 90 seated the four slidably mounted rods 13.

The outer ends of the rods 13 pass through and are secured in or to the inwardly turned flanges 14 and 15 of the inner cylinder or casing 16, which is secured to the outer concentric cylinder 17, by means of the brackets, angle irons or their equivalents 18.

The inner cylinder 16 has the longitudinal recesses or cut out portions, as indicated at 19 (see Figure 3) to receive the electric light bulbs 20, which are supported in suitable sockets which may be attached to the outer flared portions of the arms 6.

21 designates an electric heater of any suitable or conventional type which is suitably secured or supported within the guard 11, and connected with a source of electric energy by conductors of the usual character.

It will be understood from Figures 1 and 2, that the inner and outer cylinders 16 and 116

17, the brackets 18 and the rods 13 common to the flanges 14 and 15 are movable as a unit, with respect to the fixed guard as a unit, so that the outer cylinder 17 (which 5 has the function of a lamp shade, and may, if desired, be transparent or constructed of any suitable material,) together with the inner cylinder 16, is longitudinally adjustable, since a pull upon the unit composed 10 of the members 13, 16, 17 and 18 will enable the same to be drawn outwardly, the rods 13 sliding in their grooved seats 12 of the stationary open ended guard 11. By means of this construction the heat emanating from 15 the electric heater 21 can be directed or focused upon any desired point, as is evident.

The ends of the rods 13 may be secured in the flanges 14 and 15 by any suitable means, and the inner cylinder 16 may be of thin 20 sheet metal, and the outer cylinder 17 may be of glass or metal or if desired may be a skeleton frame covered with silk, as is evident.

The guard 11 and the casings 16 and 17 25 are shown as being concentrically arranged and of cylindrical shape, or in the form of open ended cylinders, but it will be apparent that any one or all of said elements may be of any other contour, if desired, 30 without departing from my invention.

The support 2 may be in the form of a pedestal to support a floor lamp or it may be a shorter standard to support a table lamp, or it may form a portion of a side bracket 35 for supporting the lamp and its adjuncts from the side wall of a room.

In Figure 3, I have shown the arms 3 as 40 elongated and provided with a counterbalance 22, which has the dual function of counterbalancing the elements to the left of the fulcrum 4 and in addition said counterbalance absorbs the vibrations of the motor 7, so that the entire device is noiseless in operation and all vibration is eliminated.

45 In the construction seen in Figures 4 to 6, I have shown substantially the same collocation of the motor 7, fan or blower 8, guard 11 and rods 13 seated in the longitudinal grooves or seats 12 and slidably therein, but 50 I employ instead of the plurality of cylinders or casings 16 and 17, the single outer cylinder or casing 22^x, which may be made of metal or glass, so as to function as a lamp shade and is provided with the in- 55 turned flanges 23 and 24, in which the ends of the rods 13 are seated or secured in any suitable manner.

It will be apparent from Figures 4 to 6, 60 that the outer cylinder 22^x and the rods 13 seated in its inturned flanges 23 and 24 move as a unit, so that when a pull is exerted upon said outer cylinder 22, the latter and the guide rods 13 move as a unit with respect to the stationary guard 11, so that the 65 heat emanating from the electric heater 21

can be directed or focused upon any desired point.

In the construction seen in Figure 7, I have shown the outer cylinder or shell 25 within which is the guard 26, within which 70 the electric heater 21 is supported, said guard 26 being open ended similar to the guard 11.

The outer end of the guard 26 is provided with a circumferential annular bead 27, 75 which is engaged by the annular groove or seat 28 of the conical open ended heat focusing shell 29, which latter obviously serves to direct the heat rays to any desired point.

The blowing and lighting elements in 80 Figure 7 are the same as already described.

I have deemed it unnecessary to show or describe in detail the electrical connections to the blowing, lighting and heating elements, as there may be of any standard or conventional type, as will be understood by 85 those skilled in this art.

Having thus described my invention, what I claim as new and desire to secure 90 by Letters Patent, is:—

1. In a device of the character stated, a combined electric heater and blower, a guard in proximity to said heater and an outer shade member telescopically supported and longitudinally movable with respect 95 to said guard.

2. In a device of the character stated, a combined electric heater and blower, a guard by which said heater is supported, longitudinally extending seats in said guard, rods 100 slidably mounted in said seats and an outer shade member movable in unison with said rods.

3. In a device of the character stated, a combined electric heater and blower, a guard supporting said heater and enclosing the fan of said blower, longitudinal seats in said guard, rods slidably mounted in said seats, an inner casing in which the ends of 105 said rods are secured and an outer casing secured to said inner casing, said outer and inner casing and said rods being telescopically adjustable as a unit with respect to said guard.

4. In a device of the character stated, a 115 combined electric heater and blower, a guard in proximity to said heater and an outer shade member telescopically supported and longitudinally movable with respect to said guard, in combination with a pivotal support for said heater, blower and guard and counterbalancing devices on the side of said pivot opposite to said heater, blower and guard.

5. In a device of the character stated, a 125 combined electric heater and blower, a guard by which said heater is supported, longitudinally extending seats in said guard, rods slidably mounted in said seats and an outer shade member movable in unison with said 130

- rods, in combination with a pivotal support for said heater, blower and guard and counterbalancing devices on the side of said pivot opposite to said heater, blower and 5 guard.
6. In a device of the character stated, a combined electric heater and blower, a guard supporting said heater and enclosing the fan of said blower, said guard being supported from said blower, longitudinal seats in said guard, rods slidably mounted in said seats, an inner casing in which the ends of said rods are secured and an outer casing secured to said inner casing, said outer and 10 inner casings and said rods being telescopically adjustable as a unit with respect to said guard, in combination with a pivotal support for said heater, blower and guard and counterbalancing devices on the side of 15 said pivot opposite to said heater, blower and guard.
7. In a device of the character stated, a combined electric heater and blower, said blower being supported in proximity to said heater, and an outer shade member, telescopically supported and longitudinally movable with respect to said heater.
8. In a device of the character stated, a combined electric heater and blower, a guard in proximity to said heater and an outer shade member telescopically supported and longitudinally movable with respect to said guard, in combination with a support, an arm carrying said heater and blower and 35 pivotally mounted on said support, and a counterbalance on said arm on the side of the pivotal support opposite to said heater and blower.
9. In a device of the character stated, a combined electric heater and blower, a guard 40 by which said heater is supported, longitudinally extending seats in said guard, rods slidably mounted in said seats and an outer shade member movable in unison with said rods, in combination with a support, an arm carrying said heater and blower and pivotally mounted on said support, and a counterbalance on said arm on the side of the pivotal support opposite to said heater and blower.
10. In a device of the character stated, in combination, an electric heater and blower, said blower being supported in proximity to said heater, an electric light supported in proximity to said blower and an outer shade 55 member telescopically supported and longitudinally movable with respect to said heater.
11. In a device of the character stated, a combined electric heater and blower, a guard 60 by which said heater is supported, longitudinally extending seats in said guard, rods slidably mounted in said seats, an electric light supported in proximity to said blower and an outer shade member movable in unison with said rods.
